(57) **ABSTRACT**

A new *petunia* plant particularly distinguished by having a dark red flower color and a mounding plant habit, is disclosed.

1 Drawing Sheet

1

Genus and species: *Petunia hybrida*.
Variety denomination: 'KLEPH14248'.

BACKGROUND OF THE NEW PLANT

The present invention comprises a new and distinct variety of *petunia*, botanically known as *Petunia hybrida* and hereinafter referred to by the variety name 'KLEPH14248'. 'KLEPH14248' is a selection from a cross-pollination of the female *petunia* line 'PH-2009-1404', also known as 'KLEPH12216' (unpatented) and the male *petunia* line SUN SPUN® Red or 'Balspunred' (patent status unknown).

In July of 2010, the proprietary female *petunia* line 'PH-2009-1404' and the proprietary male *petunia* line 'Balspun-red' were cross pollinated in Latina, Italy and seeds were obtained. The seeds were sown and plants were grown for evaluation. A plant line was selected in April 2011 in Latina, Italy and named 'KLEPH14248'. In April 2011, 'KLEPH 14248' was first vegetatively propagated by terminal tip cuttings in Latina, Italy. 'KLEPH14248' was found to reproduce true to type in successive generations of asexual propagation via tissue culture and terminal tip cuttings.

SUMMARY

The following are the most outstanding and distinguishing characteristics of this new variety when grown under normal horticultural practices in Latina, Italy.

1. Dark red flower color; and
2. A mounding plant habit.

DESCRIPTION OF THE PHOTOGRAPHS

This new *petunia* plant is illustrated by the accompanying photograph, which shows a close-up of a mature flower. The plant is about 3 months-old grown in Stuttgart, Germany in May 2013.

2

The colors shown are as true as can be reasonably obtained by conventional photographic procedures.

DESCRIPTION OF THE NEW VARIETY

The following detailed descriptions set forth the distinctive characteristics of 'KLEPH14248'. The data which define these characteristics were collected from asexual reproductions carried out in Latina, Italy. Data was collected on twelve-week-old plants grown indoors in Latina, Italy under greenhouse conditions in February 2015. Color references are to The R.H.S. Colour Chart of The Royal Horticultural Society of London (R.H.S.), 5th edition (2007).

Classification:

Family.—Solanaceae.

Species.—*Petunia hybrida*.

Common name.—*Petunia*.

Variety.—'KLEPH14248'.

Parentage:

Female.—*Petunia* line 'PH-2009-1404'.

Male.—Commercial *petunia* line SUN SPUN® Red also known as 'Balspunred'.

Plant:

Form.—Medium growing.

Habit.—Mounding.

Height (from top of soil).—About 7.0 cm.

Width (horizontal plant diameter).—About 17.0 cm.

Propagation.—Terminal tip cuttings.

Time to produce a finished flowering plant.—About 14 weeks in winter under short day conditions, 7 weeks in spring.

Time to initiate and develop roots.—2 to 3 weeks.

Root description.—Moderate density, moderate branching, white roots.

Stems:

Average number (basal).—9.

Length of basal branches (from the base of the stem to the tip).—6.5 cm.

Internode length.—0.2 cm.

<i>Diameter of branches (from midpoint).</i> —0.4 cm.	5	Shape: Linear. Apex: Acute. Base: Rounded. Margin: Entire. Texture: Upper and lower surfaces: Tomentose.
<i>Stem color.</i> —RHS 144C.		<i>Pedicels.</i> —Color: RHS 137D. Diameter: 0.5 cm. Texture: Tomentose.
<i>Anthocyanin.</i> —Absent.		<i>Reproductive organs:</i>
<i>Texture.</i> —Tomentose.		<i>Stamens.</i> —Quantity: 5. Shape: Needle-like with elliptic head. Filament: Length: 1.2 cm to 1.8 cm. Diameter: 0.01 cm. Color: RHS 145D. Anther: Shape: Elliptic. Color: RHS 150D. Length: 0.25 cm. Diameter: 0.15 cm. Pollen: Color: RHS 10D.
<i>Leaves:</i>		<i>Pistils.</i> —Quantity per flower: 1. Stigma color: RHS 145A. Style color: RHS 145B.
<i>Arrangement.</i> —Alternate.		Fruit and seed set: No fruit and seed set observed.
<i>Length.</i> —4.0 cm.		15 Disease and pest/insect resistance: None observed.
<i>Width.</i> —1.8 cm.		
<i>Shape.</i> —Elliptic.		
<i>Apex.</i> —Narrowly acuminate.	10	
<i>Base.</i> —Attenuate.		
<i>Margin.</i> —Entire.		
<i>Immature and mature leaf color.</i> —Upper surface: RHS 137B. Lower surface: RHS 146B.		
<i>Texture.</i> —Upper and lower surfaces: Tomentose.		
<i>Venation pattern.</i> —Arcuate.		
<i>Venation color.</i> —Upper surface: RHS 144A. Lower surface: RHS 144B.		
<i>Petioles.</i> —Length: 0.7 cm to 1.0 cm. Diameter: 0.2 cm.	20	20 'KLEPH14248' is a distinct variety of <i>petunia</i> . 'KLEPH14248' is distinguished from its parents as described in Table 1:
Color: RHS 144D. Texture: Tomentose.		
<i>Flower bud:</i>		
<i>Shape.</i> —Irregular oblong.		
<i>Length.</i> —5.5 cm.		
<i>Diameter.</i> —0.7 cm.		
<i>Color at tight bud.</i> —RHS 59A and RHS 59B.	25	
<i>Texture.</i> —Slightly pubescent.		
<i>Inflorescence:</i>		
<i>Blooming habit (flowering season).</i> —Permanent flowering during summertime.		
<i>Inflorescence type.</i> —Cymose.	30	
<i>Number of flowers per node.</i> —1.		
<i>Lastingness of individual blooms on the plant.</i> —7 to 10 days.		
<i>Fragrance.</i> —Absent.		
<i>Flowers.</i> —Arrangement: Composed of 5 petals fused at the base. Shape: Diameter (flower face): 6.0 cm. Depth (total length of flower): 7.5 cm. Throat/Funnel: Length: 4.5 cm. Diameter (at opening): About 1.0 cm. Texture: Both inner and outer surfaces: Smooth, glabrous. Color, immature flower: Face/Margin: RHS 45B. Upper surface: RHS 45B. Lower surface: RHS 54A and RHS 54C. Color, mature flower: Face/Margin color: RHS 46B. Upper surface: RHS 46B. Lower surface: RHS 54A and RHS 54C.	35	
<i>Petals.</i> —Apex: Mucronate. Base: Fused. Margin: Entire. Strength of waviness: Weak to medium. Degree of lobation: Low.	40	
<i>Calyx arrangement.</i> —Actinomorphic, composed of 5 sepals.		
<i>Sepals.</i> —Color: Upper surface: RHS 137A. Lower surface: RHS 146A. Length: 0.9 cm. Width: 0.2 cm.	45	

COMPARISON WITH PARENTAL LINES AND KNOWN VARIETY

TABLE 1

Comparison with Parental Lines			
Trait	Variety 'KLEPH14248'	Female parent 'PH-2009-1404'	Male Parent 'Balspunred'
Plant habit	Mounding	Semi trailing	
Flower color	Darker and more stable red than 'Balspunred'		Red

'KLEPH14248' is most similar to the commercial *petunia* plant named SUN SPUN® Red also known as 'Balspunred' (patent status unknown). Differences between the two varieties are described in Table 2:

TABLE 2

Comparison with Similar Variety		
Trait	Variety 'KLEPH14248'	Commercial line 'Balspunred'
Flower color	Darker and more stable red than 'Balspunred'	Red

We claim:

1. A new and distinct variety of *petunia* plant named 'KLEPH14248' as illustrated and described herein.
